DOOR HOLDER

John Harrison, Malad City, Idaho

Application January 28, 1937, Serial No. 122,828

4 Claims. (CL. 292—271)

This invention relates to door holders or securers of the type adapted to hold a door in an open position.

An object of the invention is to provide a device that will hold a door in various open positions and prevent the door from accidentally swinging closed.

A further object of the invention is to provide a device that will automatically engage the door when it is swung open to prevent it accidentally closing.

A further object of the invention is to provide a releasing member to release said door to allow it to close or to hold said latching device inoperative if desired.

Another object of the invention is to provide such a device with means by which the door can automatically swing to a further open position.

Other objects and advantages of the invention will become more apparent from the description and drawing, in which:

Figure 1 is a front elevational view of a door with the invention applied thereto and with the door frame shown fragmentary.

Figure 2 is a view similar to Figure 1, showing the door held in an open position.

Figure 3 is an enlarged fragmentary sectional view in elevation on the line 3—3 of Figure 1.

Figure 4 is a top plan view of the device on the line 4—4 of Figure 2.

Figure 5 is an enlarged fragmentary sectional view in elevation on the line 5—5 of Figure 1.

Figure 6 is a view similar to Figure 5, on the line 6—6 of Figure 2, and

Figure 7 is a detailed view of a modified form of notched plate.

Referring more particularly to the drawing wherein like reference characters designate like or corresponding parts in the different views, 10 is an ordinary swinging door mounted by hinges 12 upon a door frame 11, and having a door knob 13 of any common construction mounted therein.

The latching mechanism comprises a plate 14 secured laterally of the door 10 by means of driven fastenings 15. The plate 14 is spaced from door 10 except the ends which are offset inwardly to bear against the door 10 and receive the fastenings 15. Plate 14 is provided with a plurality of notches 16 in its upper edge, although the plate 50 as shown has only two notches it is to be understood that any desired number could be used.

A latch 17 having one end bent to form a loop 18 to engage an eye screw 19 mounted in frame 11, is pivotally connected by means of loop 18 and eye screw 19 to frame 11. The free end of

latch 17 is turned inwardly at 20 to ride upon the upper edge of plate 14 and engage notches 15. The end then extends downwardly at 21 between plate 14 and door 10 and outwardly at 22 under the lower edge of plate 14. Thus latch 17 is held in position upon plate 14 so that it can slide back and forth upon the plate as the door is opened and closed.

A releasing member 23 is mounted upon door 10 beneath plate 14 by means of brackets 24. One end of said member 23 is bent as shown at 25 to form a handle, it being understood that any form of handle could be used instead of the spiral loop shown. Handle 25 is positioned conveniently beneath the door knob 13 where it can be easily reached. Member 23 is offset outwardly at 26 to form a lever, the purpose of which will be hereafter explained. The end of member 23 is bent downwardly at 27 to form a stop against door 10 so that handle 25 will always remain in a slightly raised position from which it can be easily grasped.

The member 23 is loosely mounted in the brackets 24 so that handle 25 can be swung upwardly rocking the lever 26 upwardly. End 22 of latch 17 will engage lever 26 when portion 20 is resting in one of the notches 16. Thus when handle 25 is lifted upwardly lever 26 will swing up lifting end 22 and releasing latch 17 from engagement with notch 16.

In Figure 7 a plate 14' is shown similar to plate 14 and having notches 16' and 16'' in its upper edge. The notches 16'' are provided with a rounded corner on one of their sides, only one such notch being shown in Figure 7, so that the door can automatically swing outwardly from one of the intermediate notches 16'' to the next notch 16'.

In operation when the door is swung open the portion 20 of latch 17 will slide along the upper edge of plate 14 until portion 20 reaches one of the notches 16 into which it will drop, or if notches 16'' are being employed the momentum may be sufficient to cause portion 20 to ride up over the round portion and onto the next notch 16'' or 16', it being understood that any number of notches 16'' may be used. If notches 16 are being employed the handle 25 may be lifted to allow door 10 to swing to a full open position. Where it is desired to close the door 10 handle 25 is lifted rocking lever 26 upward lifting end 22 and raising portion 20 out of engagement with notch 16, 16', or 16'' so that the door can be swung closed. The handle 25 being held raised

so that end 22 will slide upon lever 26 preventing portion 20 engaging any of the notches.

It is to be understood that only the preferred embodiment of the invention has been shown, the right being reserved to make such changes and modifications as will not depart from the spirit and scope of the invention.

I claim:—

1. A door securer, comprising a notched plate 10 arranged parallel to a door, a latch bar adapted to slide upon said plate and to selectively engage the notches thereon, and a rocking member adapted to engage the free end of said latch bar to permit the release of said bar from said 15 notches.

2. A door retaining device, comprising a notched plate, a latch member adapted to engage said notches, a releasing member arranged substantially parallel to said plate and having an 20 offset portion forming a lever to engage the free

end of said latch member to release it from said notches.

3. A door holder of the class described, comprising a notched plate, a latch bar adapted to slide upon the upper edge of said plate and engage said notches, a releasing member having an offset portion forming a lever, said offset portion 5 engaging the free end of said latch bar and adapted when operated to lift said latch bar out of engagement with said notches.

4. A door holder comprising a notched plate, a strand of wire forming a latch bar and adapted to engage the notches in said plate, a releasing member formed of a strand of wire and arranged beneath said plate, said member being rotatably mounted and provided with an offset portion 15 forming a lever and a looped end forming an operating handle.

JOHN HARRISON. 20
